UNITED STATES PATENT OFFICE.

GEORGE L. PIERCE, OF MANCHESTER, NEW HAMPSHIRE, ASSIGNOR, BY MESNE ASSIGNMENTS, TO HIGH SPEED RING COMPANY, OF BOSTON, MASSACHUSETTS, A CORPORATION OF MAINE.

SPINNING AND TWISTING RING.

No. 874,429.

Specification of Letters Patent.

Patented Dec. 24, 1907.

Application filed April 7, 1906. Serial No. 310,485.

To all whom it may concern:

Be it known that I, GEORGE L. PIERCE, a citizen of the United States, residing in Manchester, county of Hillsboro, and State of New Hampshire, have invented an Improvement in Spinning and Twisting Rings, of which the following description, in connection with the accompanying drawing, is a specification, like letters on the drawings representing like parts.

This invention is intended as an improvement on my application Serial No. 270,655, filed July 21, 1905. In said application, the annular part of the traveler, composed of very thin metal of light weight, is shown as sustained on a series of rests, and in practice it has been found that the annular part of the traveler is liable to become displaced, hence I have changed the construction of the flanged ring on which the traveler is moved so as to support said annulus substantially throughout its length. Furthermore I have changed the shape of the thread guiding eye to prevent the thread from becoming detached, and I have so constructed the flanged part supporting the annulus as to provide for the discharge through the same of any lint that may come off the thread.

Figure 1 shows in top or plan view a ring embodying my present improvement; Fig. 2 is a similar view with the flanged circular wall and the anti-friction member removed; Fig. 3 shows in plan and section the traveler; Fig. 4 is an enlarged detail taken through the 35 assembled ring; and Fig. 5, a cross section in the line x , Fig. 1. Fig. 6 is an enlarged top plan view of the portion of the traveler adjacent the stem 31 with said stem shown in section.

40 The rail plate a having a central opening a^4 and adapted to be connected with the usual ring rail through screws in slots 2, has an upright locking member a^x and a positioning device a^2 .

45 The ring proper herein shown comprises a metallic shell 22 having a top flange 23, the bottom flange of said plate having at one side an upturned locking member 19 and directly opposite therefrom said flange is notched, as 50 at 18, to embrace a positioning member 15 to be described. Inside the flange member 22 is located an anti-friction member or ring 21 having an inturned flange 21 x , said member being preferably composed of wood treated

with oil or other substance to render the 55 same frictionless. The third member comprising the ring is a plate 10 having an upturned flange 12 which is provided with a series of slots or openings 13, said slots being made through the wall of the flange below 60 its upper edge. The plate 10 is provided with a positioning member 15 and a locking member 14, the locking members a^x , 14 and 19 acting one with relation to the other, as provided for in my said application. The 65 traveler shown comprises a circular piece of metal 30 very thin and of light weight and having a small top and bottom face, and also having integral therewith an arm or leg which carries at its upper end a thread eye. 70 This arm or leg extends inwardly for a short distance from the annulus 30, as at 41, see Figs. 5 and 6, and then upwardly above the spinning ring, the inwardly extending portion 41 being in the same plane as the annulus and preferably being broader than the upturned portion, as shown in Fig. 6. The upper end of the arm is turned inwardly, downwardly and outwardly, as represented in Fig. 3 to form an eye or thread receiving 80 portion 32, the extremity of the upturned portion standing outwardly as at 33.

75 In the application referred to, the eye was formed by bending the extremity of the upturned arm outwardly and downwardly 85 against the upright part of the arm, and in practice it is found that sometimes the thread escapes, but by making the eye, represented in Fig. 3 herein, it is impossible for the thread 90 to escape. Further in the application referred to where the under side of the circular part 30 of the traveler was sustained at but four points, each separated at a considerable distance from the other, it was found that in some instances the traveler became dislodged 95 from its rests, consequently, I have made the upper end of the flange 12 of such shape as to substantially support all parts of the under side of the circular portion 30 of the traveler, as the latter is rotated due to the drag of the 100 thread in the eye 32. The prevention of all possibility of the traveler becoming detached is a matter of very considerable importance, and adds greatly to the desirability of a ring of the class described.

105 The walls of the shell 22 are imperforate and preferably the vertical wall of the lining member 21 is also imperforate. I find from

practice that there is sufficient suction provided by the rapid rotation of the bobbin to suck out from the apertures 13 any lint which may accumulate therein even though the vertical wall of the shell is made imperforate.

Having described my invention, what I claim as new and desire to secure by Letters Patent is:—

- 10 1. A spinning ring comprising a shell having imperforate side walls and an inturned flange at its upper end and an anti-friction member lining the shell and flange, combined with a traveler made as a ring having flat-top and bottom faces and having an upwardly extended thread guide provided with an eye and a plate having a flange upturned within said anti-friction member and sustaining the circular part of said traveler substantially throughout its length to thereby prevent the displacement of the traveler in the ring.
- 15 2. A spinning ring comprising a shell having imperforate side walls and an inturned flange at its upper end, and an anti-friction member within said shell, combined with a traveler sustainer comprising a plate having an upturned flange provided with openings situated entirely below its upper edge on

which the circular part of the traveler moves, 30 said openings enabling any lint within the ring to be discharged therefrom toward the yarn load from which it is later thrown by centrifugal action.

3. The combination with a spinning ring 35 comprising a shell having imperforate side walls and an inturned flange at its upper end, an anti-friction member lining the shell and flange, and an inner member having an upturned flange within the anti-friction member, 40 of a traveler received between said upturned flange and the anti-friction means, said traveler comprising a circular base having smooth top and bottom faces and having integral therewith an upturned arm provided with an eye formed by bending the end of said arm inwardly, downwardly and outwardly beyond the body of the arm, said upturned flange of the inner member having a bearing to sustain the traveler substantially 45 throughout its length.

In testimony whereof, I have signed my name to this specification, in the presence of two subscribing witnesses.

GEORGE L. PIERCE.
